JOSEPH W. PARKIN, OF PHILADELPHIA, PENNSYLVANIA.

CARBURETER.

1,082,762.

Specification of Letters Patent.

Patented Dec. 30, 1913.

Application filed September 29, 1909. Serial No. 520,141.

To all whom it may concern:

Be it known that I, JOSEPH W. PARKIN, a citizen of the United States, residing at Philadelphia, in the county of Philadelphia and State of Pennsylvania, have invented 5 certain new and useful Improvements in Carbureters, of which the following is a specification.

The object of my invention is to provide 10 a novel, simple and efficient carbureter for explosive engines, whereby the explosive mixture of commingled air and vaporized oil may be properly supplied to the engine during different speeds thereof.

15 The invention consists in the novel construction and combinations of parts herein-after fully described and particularly claimed.

In the drawings:—Figure 1 is a longitudinal vertical section, partly broken away, 20 of my improved invention. Fig. 2 is an elevation of a portion of the hand operated mechanism, forming a continuation of the construction shown in Fig. 1.

25 9 designates a mixing chamber in which the vaporized oil and air are commingled in forming the explosive mixture to be supplied to the engine. The mixing chamber 9 is provided with a vertical extension 10 forming an outlet opening 11. The upper end of the extension 10 is provided with a flange 12 by means of which the extension 10 may be secured to an explosive engine with the upper end 11 in registry with the 30 passageway of the engine leading to the cylinder or cylinders thereof for the purpose of supplying the explosive mixture thereto. During the operation of the engine, the piston in the cylinder thereof is 35 reciprocated, and at certain intervals communication is established between the chamber 9 and the cylinder of the engine whereby, during the movement of the piston within the cylinder, a charge of the explosive mixture is drawn from the mixing chamber 40 into the engine cylinder and is thereafter ignited to effect the operation of the engine.

The construction of an explosive engine and its operation in drawing an explosive 45 mixture from a carbureter is common and well known, and no detailed description thereof is deemed necessary herein.

The mixing chamber 9 is provided with a lateral extension 13 having a circular opening 50 in the upper portion thereof into which is fitted a ring 14 within which a valve

opening 15 is formed to afford communication between the mixing chamber 9 and the open air. The ring 14 is provided with a valve seat 16 and a circular flange 17 having 55 a tapering inner wall which extends downwardly and outwardly from the valve seat 16. The upper portion of the extension 13 of the mixing chamber is provided with projecting lugs 18 and 19 having a space therebetween and through which extends a screw 20 by means of which the lugs 18 and 19 may be drawn toward each other to clamp the ring 14 within the upper portion of the extension 13. Thus the ring 14 forms in 60 effect a part of said extension.

Closing the valve opening 15 is an inwardly opening valve 22 fitted to the valve seat 16. The valve 22 is provided with an upwardly projecting stem 23 and a head 24 on the upper end of the stem 23. The stem 23 is fitted to a guide tube 25, which projects upwardly from arms 26 formed on and extending inwardly from the ring 14. Thus the stem 23 is guided by the tube 25 65 to maintain the valve 22 in line with the valve seat 16 and permit it to be moved into and from engagement therewith. Surrounding the tube 25 and valve stem 23 is a collar 27, and interposed between the end of the 70 collar 27 and the head 24 on the valve stem is a spring 28 which encircles said stem. Surrounding the stem 23, the tube 25, and the collar 27 is a collar 29 between which and the head 24 is interposed a spring 30 which 75 encircles the spring 28 and the valve stem 23. The collar 29 is provided with an upwardly extending housing or guard which incloses the springs 28 and 30 and adjacent parts; and the collar 29 is also externally 80 screw-threaded and screwed into a boss 31 formed on a bracket 32, which is secured to and projects upwardly from the ring 14. It will thus be seen that by turning the collar 29 it may be adjusted upon the bracket 32 85 longitudinally of the stem 23 toward and from the head 24 in a manner to regulate or vary the pressure of the spring 30 for a purpose hereinafter explained.

In order to maintain the collar 29 in positions of adjustment, I provide around the lower portion thereof a series of suitably spaced vertical grooves 33 adapted to be engaged by the inner end of a head 34 on the inner end of a pin 35 arranged within 90 an opening 36 in a projection on the bracket 32. The pin 35 and its head 34 are pressed

normally toward the collar 29 by the action of a spring 37 encircling the pin 35, bearing against the head 34 and the end wall of the opening 36.

- 5 From the construction just described it will be seen that when the collar 29 is turned or adjusted longitudinally of the stem 23 the head 34, due to its rounded end, will be forced from engagement with the grooves 33, and that the spring 36 will return it into engagement with said grooves, thereby holding the collar 29 against accidental displacement from the position to which it is adjusted.
- 15 The collar 27 is mounted to slide longitudinally upon the guide tube 25 and the lower end of the collar 27 rests upon the bifurcated arm 38 of a lever 39 which is fulcrumed on the bracket 32; the other arm 20 40 of the lever 39 is pivoted to one end of a rod 41. The other end of the rod 41 is connected to one arm of a bell-crank lever 42 pivoted to a bracket 43 which may be mounted on any convenient support. The other 25 arm of the bell-crank lever 42 is pivoted to the lower end of a rod 44, the upper end of which is pivoted to a hand lever 45. This hand lever 45 is pivoted, as at 46, to a bracket 47 which may be mounted on any suitable 30 support. The free end of the lever 45 is provided with suitable handle 48 by means of which the lever may be raised and lowered on its pivot 46. The lever 45 is provided with a latch arm 49, which is pivoted there- 35 to, as at 50, and which extends to a position below the handle 48. The latch arm 49 is provided with a laterally projecting tooth 49^a which is adapted to engage notches 51 formed in a sector 52 which is formed on the 40 bracket 47. The tooth 49^a of the latch arm 49 is forced toward the notches 51 in the sector 52 by the action of a spring 53 inter- 45 posed between the handle 48 and the latch arm 49. One end of the spring 53 extends into an opening in the handle 28, while the other end of the spring 53 encircles a short pin projecting from the latch arm 49.

From the construction just described it will be seen that if the latch arm 49 be 50 pressed toward the handle 48, the tooth 49^a will be disengaged from the sector 52, and that the lever 45 may then be raised and lowered on its pivot 46 to any desired position in which it may be retained by freeing 55 the latch arm 49 and permitting the tooth 49^a to engage one of the notches 51 of the sector 52. It will also be seen that if the lever 45 be raised or lowered the collar 27 will also be raised or lowered through the 60 rod and lever connections 44, 42, 41 and 39. By thus raising the collar 27 the upper end of the spring 28 may be moved into or from engagement with the head 24, and the pressure of the spring 28 against the head 24 65 may be varied after the spring has been

moved into engagement therewith for a purpose hereinafter described.

The mixing chamber 9 is provided with a downwardly extending tubular portion 54 having an open bottom which affords communication between the mixing chamber 9 and the open air. 70

Supported adjacent the tubular portion 54 is an oil chamber 55 having an oil inlet opening 63 connected to a suitable source of oil supply. The chamber 55 has an extension 62 provided with a discharge nozzle 61 opening into the lower end of the tubular portion 54. A constant level of oil is maintained at the discharge end of the nozzle 61 80 by a float 68 within the chamber 55 operating a valve which controls the opening 63 in the usual manner.

The operation of the carburetor is as follows: As the explosive engine draws a charge 85 of the explosive mixture from the mixing chamber 9 by the action of the piston in the cylinder of the engine tending to create a vacuum therein, a quantity of air is drawn into the mixing chamber through the lower 90 open end of the tubular extension 54 thereof, and at the same time a quantity of oil is drawn into the mixing chamber 9 from the discharge end of the nozzle 61 and is at the same time vaporized by the action of the air 95 entering the mixing chamber. While the air and oil are being drawn into the mixing chamber 9 as just described, additional air is being drawn into the chamber through the valve opening 15, the action of the piston 100 in tending to create a vacuum in the cylinder drawing the valve 22 away from its seat 16 against the action of one or both of the springs 28 and 30. Thus the required explosive mixture of vaporized oil and air is 105 supplied to the engine during the operation thereof. During the operation of the engine, the greater the speed thereof, the greater is the tendency of the piston to create a vacuum in the cylinder in drawing in the 110 explosive charge, and therefore, in order to preserve as nearly as possible the proper proportion of mixture of vaporized oil and air, the two springs 28 and 30 are provided, 115 which may be adjusted to vary the spring pressure acting upon the valve 22 to hold it against its seat. That is to say, if it be desired to run the engine at a slow speed, the lever 45 will be lowered to lower the collar 27 to move the spring 28 out of engagement 120 with the head 24, and the collar 29 will be adjusted within the bracket 32 to a position in which it will cause the spring 30 to exert the proper amount of pressure upon the valve 21 to produce the proper explosive 125 mixture for the desired speed of the engine. When however, it is desired to run the engine at high speed, the lever 45 is adjusted in respect to the sector 52 not only to bring the spring 28 into engagement with the head 24, 130

but also to bring it into engagement with the head with sufficient pressure, which, in conjunction with the pressure of the spring 30, will resist the tendency to open the valve 21 sufficiently to prevent the engine at high speed from drawing an excess amount of air into the explosive mixture through the valve opening 15. It will thus be seen that by the employment of the springs 28 and 30, and their co-acting parts, a wide range of adjustment of the pressure against the valve 21 may be obtained to meet the requirements of different speeds of the engine.

My invention is especially adapted for use in connection with automobile explosive engines, and when used in this connection the bracket 47 may be mounted on a suitable part of the automobile where it may be conveniently reached by the driver in order that the driver may operate the lever 48 to properly set the spring 28 for different speeds of the engine while operating the automobile. In the drawings I have shown the bracket 47 to mount on a boss 80, which may represent a portion of the steering post of an automobile. And in the drawings I have also represented the bracket 43 to mount on the part 81, which may represent a part of the automobile frame.

I claim:

1. In a carbureter the combination of a chamber having an air inlet opening therein, an inwardly opening valve closing said opening, a stem projecting from said valve

and having a head thereon, a sleeve surrounding said stem and slidably longitudinally thereof, a lever having an arm bearing against and operative to adjust said sleeve, a spring encircling said stem and engaging said sleeve and said head, a collar surrounding said sleeve and provided with means operative to adjust said collar longitudinally of said sleeve, and a spring encircling said stem and engaging said collar and said head.

2. In a carbureter the combination of a chamber having an air inlet opening therein, an inwardly opening valve closing said opening, a stem projecting from said valve and having a head thereon, a sleeve surrounding said stem and slidably longitudinally thereof, means operative to adjust said sleeve, a spring encircling said stem and engaging said sleeve and said head, a collar surrounding said sleeve and slidably fitted thereto, said collar being screw-threaded and screwed into a part mounted on said chamber, whereby the turning of the collar will adjust it longitudinally of the sleeve, means for holding the collar in positions of adjustment, and a spring encircling said stem and engaging said collar and said head.

In testimony whereof I affix my signature in presence of two witnesses,

JOSEPH W. PARKIN.
